(57) **CLAIM**

The ornamental design for a Christmas tree stand, as shown and described.

DESCRIPTION

FIG. 1 is a top and side perspective view of the Christmas tree stand of the present invention;

FIG. 2 is a side view of the Christmas tree stand of the present invention which is a mirror image of an opposite side of the Christmas tree stand;

FIG. 3 is a rear view of the Christmas tree stand of the present invention;

FIG. 4 is a top view of the Christmas tree stand of the present invention;

FIG. 5 is a top and side perspective view of the Christmas tree stand of the present invention with leg portions thereof detached and stowed within the Christmas tree stand;

FIG. 6 is a bottom view of the Christmas tree stand of the present invention; and,

FIG. 7 is a front view of the Christmas tree stand of the present invention.
